(57) **CLAIM**

The ornamental design for a fishing rod roller guide, substantially as shown and described.

DESCRIPTION

FIG. 1 is a side elevational view of the fishing rod roller guide showing my new design, the opposite side elevational view being a mirror image thereof.

FIG. 2 is a front elevational view of the fishing rod roller guide showing my new design, the rear elevational view being an identical view thereof;

FIG. 3 is a top plan view of the fishing rod roller guide showing my new design; and,

FIG. 4 is a bottom plan view of the fishing rod roller guide showing my new design.

The broken line showing of environment in the drawings is for illustrative purposes only and forms no part of the claimed design.
